UNITED STATES PATENT OFFICE.

JOHN M. FEDDERS, OF BUFFALO, NEW YORK, ASSIGNOR TO FEDDERS MANUFACTURING COMPANY, INC., OF BUFFALO, NEW YORK, A CORPORATION OF NEW YORK.

RADIATOR-CORE.

1,185,079.

Specification of Letters Patent. Patented May 30, 1916.

Application filed May 6, 1915. Serial No. 26,295.

To all whom it may concern:

Be it known that I, JOHN M. FEDDERS, a citizen of the United States, residing at Buffalo, in the county of Erie and State of New York, have invented new and useful Improvements in Radiator-Cores, of which the following is a specification.

This invention relates to the cores of radiators which are more particularly designed for cooling the water of gas engines used for the propulsion of automobiles.

The object of this invention is to produce a core for radiators of this character which has greater radiating efficiency, in which only the water passages are constructed of standard low brass, bronze or other closely knit and non-corrosive metal while the air passages are constructed partly of common brass.

20 A radiator core of this character is shown in my pending application for Letters Patent #9900 series of 1915, and the present invention is an improvement on the construction shown in this earlier application.

25 In the accompanying drawings: Figure 1 is a fragmentary front elevation of a radiator core embodying my improvements. Fig. 2 is a vertical transverse section taken in line 2—2, Fig. 3. Figs. 3 and 4 are vertical longitudinal sections taken in the correspondingly numbered lines in Fig. 2. Fig. 5 is a horizontal section taken in line 5—5, Fig. 2. Fig. 6 is a fragmentary vertical section, on an enlarged scale, similar to Fig. 2.

35 Fig. 7 is a fragmentary perspective view of one of the walls of a water tube. Fig. 8 is a similar view of one of the radiating webs. Fig. 9 is a fragmentary vertical section similar to Fig. 6 but showing a slightly modified construction.

40 Similar characters of reference indicate corresponding parts throughout the several views.

In its general organization this core is so constructed as to produce a plurality of upright water passages or tubes 1 which open at their upper and lower ends into the usual upper and lower headers forming part of the radiator, and a plurality of horizontal 50 air passages or conduits 2 arranged between the water passages or tubes and extending fore and aft of the radiator.

Each of the water tubes is of zig-zag form so that the water in passing through the same 5 takes a tortuous path and thereby increases

the cooling area of the same which is exposed to the air on the exterior of the tube. In its preferred form each of these tubes is constructed of two strips 3, 3 of sheet metal each of which is corrugated into zig-zag 60 form and which are assembled so that the corrugations of these tubes fit into each other but are spaced apart so as to leave a water passage therebetween. At the opposite longitudinal edges of the strips forming 65 the walls of a tube the same are off-set toward each other, as shown at 4 in Fig. 5, and the off-sets at corresponding longitudinal edges of the tube walls engage with each other and are connected by soldering or 70 other suitable means, thereby forming the closures at the longitudinal edges of the tube. The upper and lower transverse edges of the walls or strips of each tube are, however, disconnected from each other so as 75 to permit the same to communicate with the upper and lower headers of the radiator with which they are assembled in the usual and well known manner.

At the turns of the walls of the several water tubes the same are provided with flattened bearing faces 5, 6 which faces of each wall form alternately the convex and concave sides of the turns in the respective wall. In the assembled position of the two walls of 80 a water tube each convex flat face 5 of one wall is arranged in line with a concave flat face 6 of the companion wall of the tube, as shown in Fig. 2.

Between the several water tubes are arranged a plurality of radiating webs or fins 7 which engage with these tubes and serve to carry off some of the heat of the water passing through the tubes and deliver it to the air which passes lengthwise through the 90 radiator in contact with these radiating webs. Each of these radiating webs is preferably constructed of a strip of sheet metal which is corrugated into zig-zag or tortuous form and each turn in this strip is 100 preferably constructed to provide a flat bearing face 8. As shown in Figs. 1 and 2, two of such radiating webs are arranged between two adjacent water tubes in such manner that these webs engage with each other and also engage respectively with the opposing walls of the water tubes with which they co-operate. If desired, however, the number of such radiating webs may be varied to suit the capacity of the radiator 105 110 115

which is to be made or to suit other conditions. In the organization shown in Fig. 2, the flat faces at the turns of each radiating web engage alternately with the convex flat faces of a wall of one water tube and the convex sides of the flattened faces on the companion radiating web, so that as a whole the radiator core presents a cellular appearance when viewed either from the front or from the rear side thereof.

At its upper and lower transverse edges each of the radiating webs is secured to the corresponding edges of the companion tube wall with which the same is associated, preferably by means of a lock joint 9, as shown in Fig. 2, and is also connected with the corresponding ends of the companion radiating web or strip, preferably by a solder joint 10, thereby closing the spaces of the core between the ends of adjacent tubes and preventing the water from leaking out of the headers.

The several water tubes and radiating webs or fins are also preferably interlocked with each other so as to stiffen the radiator core and prevent displacement of its members, relatively to each other and still retain sufficient flexibility of the same to permit the core to adapt itself to the slight changes in the position of the parts on which the radiator is mounted. For this purpose each of the convex faces of the walls of each radiator tube is provided with an outwardly extending projection 11 which preferably has the form of a longitudinal bead or rib and the adjacent flattened turn of the companion radiating web is provided with a seating aperture 12 which preferably has the form of a longitudinal slot and receives the companion bead or rib, thereby interlocking these parts. The metal displaced from the webs for forming the slots 12 is preferably turned outwardly to form horizontal flanges 12¹ above and below each slot, as shown in Figs. 2, 5, 6 and 8 for increasing the radiating efficiency of the core, or this metal may be entirely removed, as shown in Fig. 9. By thus providing the flat faces 6 of the webs with slots which receive the beads 11 of the water tube walls the presence of a double thickness of metal between the opposing surfaces of the water tube walls and the radiating webs is reduced to a minimum inasmuch as the beads 11 are exposed to the atmosphere and thereby increasing the radiating or cooling capacity of the core accordingly. The flattened intermediate turns of the radiating webs which alternate with those engaging the water tube are also provided with complementary interlocking projections 13 and recesses 14, the projections having preferably the form of longitudinal beads or ribs which are formed on one of the webs and the companion recesses of the other radiating web

having the form of corresponding grooves or channels so as to receive the beads of the other web and produce an interlocking connection between the same. The upright edges of the webs may also be offset, as shown at 15 for the purpose of fitting the offset portions of the water tube walls or strips.

In order to still further increase the radiating efficiency of the core each of the inclined sections 7¹ of the webs 7 which alternate with the bearing faces 8 thereof is provided with one or more lips or wings 8¹ which are stamped out of the metal of the sections 7¹ and bent laterally therefrom so as to project into the path of the air passing through the radiator core. A plurality of such lips or wings are preferably formed in a longitudinal row on each web section 7¹ and the several lips in each row are arranged in different planes so that each lip stands in a different part of the air passage, whereby the front edge of each lip is engaged by the current of air independently of the other lips and thus aids in transferring the heat of the water in the tubes to the atmosphere.

The ends of the radiating webs adjacent to the corresponding ends of the water tubes are preferably covered with solder or other material, so that any pores in these parts of the webs will be closed and leakage of water through the same is prevented.

I claim as my invention:

1. A radiator core comprising a plurality or tortuous water tubes, and tortuous radiating webs arranged between adjacent tubes and in contact therewith and each web provided intermediate of its contact places with rows of lips, the lips of each row being arranged in different planes and the bases of the several lips in each row being arranged lengthwise in line.

2. A radiator core comprising a plurality of water tubes each of which is of zig-zag form and provided at its turns with contact faces, and a plurality of radiating webs arranged between adjacent tubes, each web being of zig-zag form and having contact faces at its turns which engage with the corresponding faces of an adjacent tube, the faces of said tubes being provided with projections and the faces of the webs having slots which receive said projections.

3. A radiator core comprising a plurality of water tubes each of which is of zig-zag form and provided at its turns with contact faces and a plurality of radiating webs arranged between adjacent tubes, each web being of zig-zag form and having contact faces at its turns which engage with the corresponding faces of an adjacent tube, the cooperating faces of each tube and the adjacent web being flat and provided with complementary projections and slots which in-

terlock with each other, and each web being provided adjacent to its slots with laterally projecting flanges.

4. A radiator core comprising a plurality of water tubes each of which is of zig-zag form and provided at its turns with contact faces and a plurality of radiating webs arranged between adjacent tubes, each web being of zig-zag form and having contact

faces at its turns which engage with the corresponding faces of an adjacent tube, the co-operating faces of each tube and the adjacent web being flat and provided with complementary projections and slots which interlock with each other and each web being provided on opposite sides of each of its slots with laterally projecting flanges.

JOHN M. FEDDERS.
